UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

FEEDING MECHANISM FOR SEWING-MACHINES.

1,311,880.

Specification of Letters Patent.

Patented Aug. 5, 1919.

Application filed December 8, 1917. Serial No. 206,200.

To all whom it may concern:

Be it known that I, ALBERT H. DE VOE, a citizen of the United States, residing at Westfield, in the county of Union and State 5 of New Jersey, have invented certain new and useful Improvements in Feeding Mechanisms for Sewing-Machines, of which the following is a specification, reference being had therein to the accompanying drawings.

10 This invention relates to feeding mechanisms for sewing machines, and more particularly to that type of feeding mechanisms in which a four-motion upper feed-dog rises and falls reciprocally with a presser-foot.

15 The invention has for its object to provide a simple and durable feeding mechanism, compactly arranged to provide an unobstructed space under the overhanging arm and to provide readily accessible means for 20 adjusting the extent of the feed-dog movements.

In its preferred embodiment the invention comprises a feed-dog sustained by a carrier fulcrumed upon a supporting rock-lever pivotally carried by the presser-bar. Two rock-shafts are journaled to oscillate upon a common axis in bearings provided on the head of the machine and are actuated from the 25 driving shaft of the machine by connections therewith adjustable independently of each other. One of the rock-shafts actuates the supporting rock-lever to impart feeding movements to the feed-dog and the other rock-shaft oscillates the feed-dog carrier 30 upon its fulcrum to impart rising and falling movements to the feed-dog and to lift the presser-bar when the downward movement of the feed-dog is arrested by the throat-plate or the fabric upon it.

40 In the accompanying drawings Figure 1 is a rear side elevation, partly in section, of a machine having its cloth-plate removed and embodying the present improvements. Fig. 2 is a front end elevation of the machine 45 with the face-plate of the bracket-arm removed. Fig. 3 is a sectional view on the line A—A, Fig. 1, and Fig. 4 is a detail perspective view of the feed-dog and presser-foot.

50 The machine is constructed with the usual base 1, hollow-standard 2 and overhanging bracket-arm terminating in the head 3. Journaled in the base 1 is the main or driving shaft 4 provided with the belt-wheel 5

and balance-wheel 6. The shaft 4 is formed 55 with a crank 7 embraced by the lower end of a pitman 8 whose upper end is pivotally connected with the lateral arm 9 of the needle-actuating rock-shaft 10, journaled in bearings provided in the overhanging 60 bracket-arm of the machine. The forward end of the rock-shaft 10 is connected by means of a crank-arm 11 with a link 12 pivotally secured to a collar 13 on the vertically reciprocable needle-bar 14 carrying the 65 needle 15. Coöperating with the needle 15 below the throat-plate 16 in the formation of stitches is a looper 17, adjacent which is shown a trimmer 18, the construction and operation of which is unessential to an understanding of the present invention.

Mounted for vertical movement in the head 3 is the presser-bar 19 sustaining the presser-foot 20 secured thereto by means of the screw 21, the spring 22 acting to yieldingly press the presser-foot upon the cloth-plate 16. The lifter-bracket 23 is slidingly supported upon the presser-bar 19 by means of sockets formed in the spaced ears 23^a and 23^b, and is provided with the roller-stud 24 75 normally resting upon the hand lifter-lever 25. The lifter-bracket is also provided with a stud-pin 26 entering an aperture in one end of a lever 27 fulcrumed upon a stud-screw 28 on the bracket-arm. The other end 80 of the lever 27 is connected with the treadle-rod 29.

Two spaced collars 30 and 31 are secured upon the presser-bar 19, the collar 30 being positioned immediately above the ear 23^b of 90 the lifter-bracket to afford means for lifting the presser-bar upon operation of either of the lifter-levers. Bridging the space between the collars 30 and 31 is a plate 32 to which is secured a fulcrum-pin 33 for the 95 supporting rock-lever 34. Fulcrumed upon the lower end of the lever 34 by means of a stud-pin 35 is an elbow-lever or feed-dog carrier 36 to the lateral arm of which is secured the feed-dog 37 bifurcated to admit 100 the fabric engaging portion of the presser-foot 20. Journaled upon bearing-bosses 38 and 39 formed upon the rear side of the overhanging arm of the machine is a hollow or tubular rock-shaft 40 to the rearward end 105 of which is secured a collar 41 having a laterally extending slotted arm 42, to which is pivotally secured in adjustable positions the

upper end of a pitman 43 formed, at its lower end, with a strap embracing an eccentric upon the driving shaft 4. Journalized within the tubular shaft 40 is a second rock-shaft 44 to which is secured a collar having a laterally extending arm 45 to which is pivotally secured in adjustable positions the upper end of a pitman 46 formed at its lower end with a strap embracing a second eccentric 47 upon the driving shaft 4. The connections described afford means for actuating the rock-shafts to any predetermined extent of movement within the range of the adjustments provided.

To the forward end of the rock-shaft 40 is secured a collar having a depending arm 48 pivotally connected by means of a pivot screw 49 with one end of a link 50 of which the other end is connected in like manner by means of a pivot screw 51 with the upper end of the supporting rock-lever 34. The actuation of the rock-shaft through the described connections transmits vibratory movements to the rock-lever 34 and through its connection with the feed dog carrier 36 imparts feeding movements to the feed-dog 37. The feed-dog lifting movements are derived from the rock-shaft 44 to the forward end of which is secured a collar 52 having a depending arm 53, which transmits the movements of the rock-shaft to the upwardly extending arm of the feed-dog carrier 36 through the intermediary of the link 54 and the pivot-screws 55 and 56. The rocking movements thus imparted to the feed-dog carrier 36 upon its fulcrum 35 cause the rising and falling movements of the feed-dog. The rock-shaft 44 has a greater range of movement than is necessary to return the feed-dog from its lifted position into contact with the material upon the throat-plate, the continued movement of the rock-shaft 44 after the feed-dog 37 contacts with the material being expended in lifting the presser-foot with the feed-dog acting as the fulcrum. The lifting of the feed-dog above the material after the completion of its feeding movement permits the presser-spring 22 to return the presser-foot upon the material. The fabric engaging portion of the feed-dog 37 is preferably slightly curved and has a rolling action during its feeding movement, throughout which the uniformity of the fabric gripping action of the feed-dog is consequently maintained.

Having thus set forth the nature of the invention, what I claim herein is:—

1. A four-motion upper feeding mechanism for sewing machines comprising a feed-dog, a supporting rock-lever, a feed-dog carrier fulcrumed upon and sustained solely by said rock-lever, actuating means acting through said rock-lever to impart feeding movements to said feed-dog, and means 60 for rocking said carrier upon its fulcrum

for imparting rising and falling movements to said feed-dog.

2. In a sewing machine, the combination with a reciprocally rising and falling presser-foot and feed-dog, a presser-bar sustaining said presser-foot, a supporting rock-lever sustained by the presser-bar, and a feed-dog carrier fulcrumed upon said rock-lever, of means for actuating said rock-lever to impart feeding movements to said feed-dog, and means for rocking said feed-dog carrier upon its fulcrum to impart reciprocal movements to said presser-foot and feed-dog.

3. In a sewing machine, in combination, a reciprocally rising and falling presser-foot and feed-dog, a presser-bar sustaining said presser-foot, a supporting rock-lever sustained by the presser-bar, a feed-dog carrier fulcrumed upon said rock-lever, two rock-shafts, means for actuating said rock-shafts, an operative connection between one of the rock-shafts and said rock-lever for imparting feeding movements to said feed-dog, and an operative connection with the other rock-shaft for rocking said feed-dog carrier upon its fulcrum to impart reciprocal movements to said feed-dog and presser-foot.

4. In a sewing machine, in combination, a feed-dog, a supporting rock-lever, a feed-dog carrier fulcrumed thereon, two rock-shafts mounted for oscillation upon a common axis, an actuating shaft, driving connections adjustable independently of each other between said actuating shaft and each of said rock-shafts, means for actuating said rock-lever to impart feeding movements to said feed-dog from one of the rock-shafts, and an operative connection between the other rock-shaft and the feed-dog carrier for rocking said carrier upon its fulcrum to impart rising and falling movements to said feed-dog.

5. In a sewing machine, in combination, a presser-bar, a presser-foot sustained by said presser-bar, a supporting rock-lever fulcrumed upon said presser-bar, a feed-dog carrier fulcrumed upon said rock-lever and sustaining a feed-dog having a curved fabric engaging surface, means for vibrating said rock-lever to impart feeding movements to said feed-dog, and means for rocking said carrier upon its fulcrum to impart rising and falling movements to said feed-dog and to cause said feed-dog to have a rolling contact with the fabric throughout its feeding movements.

6. In a sewing machine, in combination, a presser-bar, a supporting rock-lever fulcrumed upon said presser-bar, a feed-dog carrier fulcrumed upon said rock-lever, two rock-shafts mounted for oscillation upon a common axis, means for actuating said rock-shafts, operative connections between one of

said rock-shafts and said rock-lever for imparting feeding movements to said feed-dog, operative connections between the other rock-shaft and the feed-dog carrier 5 for rocking said feed-dog carrier upon its fulcrum to impart rising and falling movements to said feed-dog, and a throat-plate

adapted to intercept the downward movement of the feed-dog to cause lifting movements of the presser-bar alternating with 10 the rising movements of the feed-dog.

In testimony whereof, I have signed my name to this specification.

ALBERT H. DE VOE.
